(No Model.)

D. SNYDER.

CHURN.

No. 365,205.

Patented June 21, 1887.

UNITED STATES PATENT OFFICE.

DAVID SNYDER, OF BLOOMVILLE, OHIO.

CHURN.

SPECIFICATION forming part of Letters Patent No. 365,205, dated June 21, 1887.

Application filed October 25, 1886. Serial No. 217,123. (No model.)

To all whom it may concern:

Be it known that I, DAVID SNYDER, a citizen of the United States, and a resident of Bloomville, in the county of Seneca and State 5 of Ohio, have invented certain new and useful Improvements in Churns; and I do hereby declare that the following is a full, clear, and exact description of the invention, which will enable others skilled in the art to which it applies 10 to make and use the same, reference being had to the accompanying drawings, which form a part of this specification, and in which—

Figure 1 is a perspective view of my improved churn. Fig. 2 is a vertical sectional view of the same, and Fig. 3 is a similar view taken on a plane at right angles to the former.

Similar numerals of reference indicate corresponding parts in all the figures.

My invention has relation to that class of churns in which two dashers having laterally-projecting fingers or strips are reciprocated in opposite directions within the churn-body with the fingers intermeshing; and it consists in the improved construction and combination of parts of the same, as hereininafter more fully described and claimed.

In the accompanying drawings, the numeral 1 indicates a rectangular box or casing, tapering slightly toward the upper end and forming the churn-body, and the open top of this body is covered by means of a larger removable cover, 3, and a smaller cover, 4, which is held in place upon the top by means of turn-buttons 5, having hooked inner ends, 6, engaging lugs or studs 7 upon the upper side of the small cover. A shaft, 8, is journaled in bearings 9 and 10 in the upper ends 30 of two of the side pieces, one of the bearings, 9, being formed with a short upwardly-extending groove, 11, in the side piece, while the other bearing, 10, is provided with a longer upwardly-extending groove, 12, in the block 13, forming the bearing. The shaft is provided with a downwardly-projecting arm, 14, at the end near the bearing having the short slot, and this arm is provided with a number of laterally-projecting fingers, 15. A lever, 16, is pivoted upon the shaft near the other bearing, projecting with its upper han-

dle-arm, 17, through a slot, 18, in the edge of the small cover, while the downwardly-projecting portion of the lever is provided with a number of laterally-projecting fingers, 19, 55 meshing into the spaces between the fingers of the arm 14. The rock-shaft is provided with an upwardly-projecting short arm, 20, projecting through the slot in the cover of the churn, and this arm is pivoted at its upper end to the lower arm of a small lever, 21, fulcrumed upon a stud, 22, projecting from an upwardly-projecting bracket, 23, upon the smaller cover, and having a longitudinal slot, 24, at its upper end, by which it is pivoted to 60 a stud, 25, projecting from the side of the handle-arm 21. It will now be seen that as the handle-arm is rocked the arm having the fingers will be rocked inside of the churn-body, and the other arm will be rocked in 65 the opposite direction on account of the upwardly-projecting short arm being pivoted to the lever having the slot at its upper end, so that the contents of the churn will be thoroughly agitated by the two dashers rocking 70 in opposite directions. The motion of rocking the lever-arm will be an easy motion for the person operating the churn, and the contents of the churn may be inspected whenever desired by simply removing the larger cover; 75 and it will be seen that the dashers having the laterally-projecting fingers may be easily cleaned, all parts of the said dashers being easily accessible. The bottom of the churn-body is preferably slightly concave, to correspond to the arc described by the lower ends 80 of the dashers.

Having thus described my invention, I claim and desire to secure by Letters Patent of the United States—

In a churn, the combination of an upwardly-tapering rectangular churn-body, a shaft journaled with its ends in bearings at the upper ends of two of the side pieces, and having a downwardly-projecting arm near one end provided with laterally-projecting fingers and having an upwardly-projecting short arm, a lever pivoted upon the end of the shaft, and formed with an upwardly-projecting handle-arm and with a downwardly-projecting arm 95 having laterally-projecting fingers meshing with the fingers of the other arm, and a lever 100

fulcrumed upon a stud projecting from a bracket upon the cover of the body and pivoted at one end to the upper end of the upwardly-projecting short arm, and having a longitudinal slot at its upper end pivoted and sliding upon a stud upon the handle-arm, as and for the purpose shown and set forth.

In testimony that I claim the foregoing as my own I have hereunto affixed my signature in presence of two witnesses.

DAVID SNYDER.

Witnesses:

OLVIS WILSON,
J. R. WILSON.
